CHAIR IRON

David R. Collier and Henry W. Sheldrick, Gardner, Mass., assignors to Collier-Keyworth Company, Gardner, Mass., a corporation of Massachusetts

Application May 8, 1937, Serial No. 141,474

4 Claims. (Cl. 155—157)

This invention relates to chair irons for office chairs or the like, having backs which yield rearwardly against spring pressure from an adjusted initial position and which are also vertically adjustable.

It is an object of the invention to provide a clamping device to hold the back in vertically adjusted position having a control member offset to a side of the chair iron for ready accessibility by the occupant of the chair.

It is another object of the invention to provide a back which can quickly and easily be removed from and returned to the chair structure.

15 It is a further object of the invention to provide a structure such that the rear of the chair is free from undesirable projections.

For a more complete understanding of the invention, reference may be had to the disclosure 20 of an embodiment thereof in the following description, and in the accompanying drawing of which:

Figure 1 is a rear elevation of a chair embodying the invention.

25 Figure 2 is a fragmentary section on the line 2—2 of Figure 1.

Figure 2a is a sectional view on line 2a—2a of Figure 2.

Figure 3 is a fragmentary section on the line 3—3 of Figure 1.

30 Figure 4 is a section on the line 4—4 of Figure 3.

Figure 5 is a perspective view of certain parts of the structure.

35 As illustrated on the drawing, the invention may be embodied in a chair iron for office chairs such as the one illustrated in Figure 1, this chair having the usual base or pedestal 10 into which projects the spindle 12 of the chair iron, generally indicated at 14.

40 A seat 16 is mounted on the iron and the chair also includes a back 18 which is rockable rearwardly against the pressure of a spring 20 illustrated in Figure 2. The structure of the chair iron for the most part is shown as similar to that described and illustrated in the application of Henry W. Sheldrick, Serial No. 84,277, filed June 9, 1936. As therein shown, the chair iron may comprise a seat support having a pair of longitudinally extending members 24 to

45 which is pivotally attached, as at 26, a member consisting of a pair of side plates 30 connected by a bridging piece 32 so that this member rocks as a unit about a horizontal axis passing through the pivots 26. Such rocking movement is against the spring 20 which is supported by a bolt 34 projecting through and having a head supported on a transverse frame element 36 which extends between the longitudinal members 24. The lower end portion of the bolt 34 is threaded to receive 50 a nut or hand wheel 38 against which the lower

end of the spring 20 seats, the hand wheel 38 being manually rotatable to increase or diminish the initial compression of the spring 20.

5 A back bracket 40 is pivotally attached to the side portions 30 of the rockable member. The back bracket preferably comprises an upright rectangular plate having forwardly projecting ears or flanges 42 which are respectively pivoted as at 44 to the side portions 30 of the rockable member. Thus the back bracket can be angularly 10 adjusted relatively to the rockable member but can rock as a unit with that member about the pivots 26. The angular relation between the bracket 40 and the rockable member may be controlled by any suitable device, such as a link 46 15 which is connected at one end to the upper portion of the bracket 40, and at the other end to an approximately horizontal bell crank 50 which is rockable about a pivot 52 so as to pull or push the link 46. The bell crank 50 is actuated by 20 the rotation of a shaft 54 which is in threaded engagement with an element 56 pivotally attached as at 58 to the bell crank 50, or as more fully illustrated and described in the said Sheldrick application Serial No. 84,277. The shaft 54 extends transversely with respect to the chair, 25 a suitable hand wheel 60 being preferably mounted at its outer end so as to be conveniently reached by the occupant of the chair. Rotation of the hand wheel 60 thus controls the angular relation between the back bracket 40 and the 30 rockable member so that the normal position of the back 18 is thus adjusted, from which normal position the back will yield rearwardly under pressure together with the bracket 40 and the rockable member rocking as a unit about the 35 pivots 26.

According to the present invention, improved structure is provided for adjustably securing the back 18 to the bracket 40. To this end, the bracket is provided with a vertical slot 70 which extends upward from the lower end of the bracket nearly to the top thereof. In order to compensate for the weakening of the bracket by this slot, a channel member 72 is provided to span the slot, this channel member preferably extending from the top to the bottom of the bracket 40, as indicated in Figure 2.

The back 18 is directly mounted upon a back plate 74 which engages the back of the bracket 40 at the corners, as indicated in Figure 3. This back plate is vertically adjustable and is ordinarily clamped in adjusted position against the bracket 40. As indicated in Figure 3, the central portion 76 of the plate 74 is offset rearwardly and bulges away from the face of the bracket. The end portions of the plate may be bent along their side edges as at 78 to form stiffening flanges. In order to clamp the plate 74 tightly against the bracket 40, a plate 80 is provided which is pref- 60

erably bulged rearwardly both longitudinally and transversely, as indicated in Figures 2 and 3. The plate 80 is secured to the outer end of an element 82. This element extends through the slot 70 and has a head 84 engaging the front face of the bracket 40 within the channel of the member 72. The element 82 also extends through an aperture 85 in the plate 74 and also through an aperture 86 in the plate 80 and is headed over against the outer face of the plate 80, as indicated in Figure 3. In order to clamp the back plate 74 in adjusted position, a wedging element is provided consisting of a shaft 100 having a tapered end 102 entering between the plates 74 and 80. The shaft 100 has a threaded portion 104 which is in threaded engagement with an ear 106 at an end of the plate 74. The tapered end 102 of the shaft may be suitably guided by the rounded heads of a pair of rivets 110 which are secured through the plate 80. The heads of these rivets may also provide a purchase for the wedging effect of the tapered end 102. On the outer end of the shaft 100 may be mounted a hand wheel 112 by which the shaft may conveniently be operated by the occupant of the chair, this operating wheel 112 being located, as indicated in Figure 1, at the side of the seat so as to be within easy reach. Rotation of the shaft 100 in one direction causes the tapered end 102 to advance toward the left and to wedge the adjacent end of the plate 80 away from the plate 74 and its opposed end portion against the back face of the plate, both these actions forcing the plate 74 forward against the bracket 40 which it engages along the roots of the flanges 42, clamping it in adjusted position. When the shaft 100 is backed away toward the right, the plate 74 with its back 18, is released for vertical adjustment, the element 82 then riding in the slot 70. The hand wheel 112 is so positioned that it may be grasped by one hand of the chair occupant while he grasps the back of the chair on the opposite side with the other hand. The back may then be loosened, adjusted to suit the occupant while he is in a normal sitting position, and then tightened. In order to keep the plate 80 roughly parallel to the plate 74 when the former is loosened, ears 105 are provided on the plate 80 to extend forward, overlapping the upper flanges 78 of the plate 74. The aperture 86 is shown as above the horizontal center of the plate 80 in order to increase the effective lever arms to the points of engagement of the plate 80 against the plate 74 to better resist backward pressure exerted on the chair back by the occupant. Since the slot 70 is open at its lower end, the back assembly (consisting of the back 18, the plate 74, the lever 80 and the bolt 82) may be moved from the bracket 40 as a unit. In order to prevent this assembly from falling clear of the bracket 40 when it is desired only to adjust the back vertically, a catch is provided. This catch, as indicated in Figure 2, may consist of a tongue struck up from a strip of spring metal 122 which is secured at its upper end to the channel member 72 as by a rivet 124. The tongue 120 projects through an aperture 126 in the lower portion of the channel member, the strip 122 ordinarily lying against the forward face of the channel member. The tongue 120 is thus in the path of movement of the bolt head 84 and normally acts to positively stop the downward movement of the bolt head so as to prevent the back assembly from becoming entirely disengaged from the bracket 40 in the course of vertical adjust-

ment of the back. When, however, it is desired to remove the back assembly from the bracket, the lower end 130 of the strip 122 may be pressed toward the right, as indicated in Figure 2, so as to retract the tongue 120 from the path of the head 84. This permits the ready removal of the back assembly from the bracket.

From the foregoing description of an embodiment of this invention, it should be evident to those skilled in the art that various changes and modifications may be made therein without departing from the spirit or scope of this invention as defined by the following claims.

We claim:

1. A chair iron comprising a seat support, an upright back bracket carried by said seat support and having a vertical slot extending up from the lower edge thereof, a channel member secured to the forward face of said bracket bridging said slot, a vertically adjustable back plate engaging the back of said bracket, means for clamping said plate in adjusted position against said bracket, said clamping means including an element extending through said slot and having a head disposed in said channel, and means cooperating with said element to effect the clamping action, and spring catch means near the lower end of said slot normally disposed in the path of said head to limit the downward movement thereof.

2. A chair iron comprising a seat support, a back bracket carried by said support, a back plate vertically adjustable on said bracket, and means for clamping said plate in adjusted position, said means comprising a member positioned adjacent to said plate, an element attached to said member and extending through said plate and bracket, said element having a head engaging the forward face of said bracket, and wedging means between said member and plate for pressing said plate against said bracket.

3. In a chair iron, an upright back bracket having a vertical slot therein, a back plate engaging the back of said bracket, and means for clamping said plate against said bracket in adjusted position, said clamping means comprising a member behind said plate, an element extending rearwardly through said slot and plate and secured to said member between the ends thereof, said element having a head engaging the forward face of said bracket and serving as a fulcrum for said member, and a rotatable shaft having a tapered end engaging between said plate and member, said shaft having a threaded portion cooperating with a portion of said plate to advance the tapered end axially when rotated so as to rock said member on its fulcrum and clamp said plate against said bracket.

4. In a chair iron, an upright back bracket, a pair of transversely extending members behind said bracket, one of said members having a central portion engaging the back of the bracket and bulging away therefrom, the other said member engaging the rear face of said one member, an element securing said bracket and members together, an ear on an end of one of said members with a threaded aperture, and a shaft having a threaded portion engaging in said aperture and a tapered portion between said members movable axially by rotation to spread said members and thereby to clamp them against said bracket.
